(57) **CLAIM**

The ornamental design for a flat panel display, as shown and described.

DESCRIPTION

FIG. 1 is a front perspective view of our design for a frameless electronic flat panel display;

FIG. 2 is a top view thereof;

FIG. 3 is a front view thereof;

FIG. 4 is a bottom view thereof;

FIG. 5 is a rear view thereof;

FIG. 6 is a left side view thereof;

FIG. 7 is a right side view thereof;

FIG. 8 is a bottom view of a second embodiment thereof, in which the front perspective, top, front, rear, left side, and right side views are the same as those in FIGS. 1, 2, 3, 5, 6, and 7, respectively;

FIG. 9 is a rear view of a third embodiment thereof, in which the front perspective, top, front, bottom, left side, and right side views are the same as those in FIGS. 1, 2, 3, 4, 6, and 7 respectively;

FIG. 10 is a front perspective view of a fourth embodiment thereof;

FIG. 11 is a top view thereof;

FIG. 12 is a front view thereof;

FIG. 13 is a bottom view thereof;

FIG. 14 is a rear view thereof;

FIG. 15 is a left side view thereof;

FIG. 16 is a right side view thereof;

FIG. 17 is a bottom view of a fifth embodiment thereof, in which the front perspective, top, front, rear, left side, and right side views are the same as those in FIGS. 10, 11, 12, 14, 15, and 16 respectively; and,

FIG. 18 is a rear view of a sixth embodiment thereof, in which the front perspective, top, front, bottom, left side, and right side views are the same as those in FIGS. 10, 11, 12, 13, 15, and 16, respectively.

The side support blades represented by broken lines in FIGS. 10-18 are shown for environment only, and form no part of the claimed design, and the broken lines shown in FIGS. 10 and 12 that are immediately surrounding the oblique lines are for the purpose of illustrating portions of the display panel.
